UNITED STATES PATENT OFFICE

JOHN J. RYAN, OF CHICAGO, ILLINOIS

MARCEL WAVER

Application filed July 2, 1930. Serial No. 465,253.

My invention relates to a bonnet-like structure adapted to be placed on a head of hair to facilitate formation of Marcel waves in the hair, and one of the objects of the present invention is the provision of a collapsible structure for this purpose.

A further object of the invention is the provision of improved means for securing together the members of a bonnet-like structure adapted for use in effecting Marcel waves in the hair.

Another object of the invention is the provision of waterproof coverings for the metal members of the bonnet-like structure to lessen the cost of construction and prevent corrosion of such metal members.

A still further object is to provide a collapsible hair waving structure which has a flexible or fabric front member to which 20 water-proof, relatively stiff, wire members are attached; which has a flexible or fabric neck member fixed to the front member; which has a flexible rear member connecting the various stiff members; and which has 25 flexible ties connected to the front member for fastening the structure in place on the head of a person.

Other objects of the invention will appear hereinafter, the novel features and combinations being set forth in the appended claims.

In the accompanying drawings—

Fig. 1 is a perspective view of a Marcel waver embodying my invention;

Fig. 2 shows the Marcel waver collapsed;

35 Figs. 3, 4, 5 and 6 are detail views showing the mechanism for connecting together the members of the Marcel waver;

Fig. 7 is a perspective view of a modified Marcel waver particularly adapted for mar- 40 celling a pompadour head of hair;

Fig. 8 is a plan view of the structure shown in Fig. 7; and

Fig. 9 is a plan view of a Marcel waver, 45 partly broken away, to show another modification.

To accomplish the main object of the invention, I provide a bonnet-like structure which may be collapsed as shown in Fig. 2 so as to occupy a very small space during transportation or while held in stock. As shown

in Fig. 1, the Marcel waver is a bonnet-like structure adapted to fit over a head of hair. This bonnet-like structure comprises a front face member 10 which when on a person's head is continuously curvilinear from end to end and inverted U-shaped in contour so as to fit over the forehead and down the sides of the face. This front face member is flexible and collapsible and is preferably made of fabric such as tape and may be ornamented 55 as desired and made in various colors.

The lower ends of the front face member 10 are connected to a horizontal U-shaped neck member 11 which is also of flexible collapsible material such as tape fabric so as to be comfortable when in use and so as to facilitate collapsing of the Marcel waver as shown in Fig. 2. The horizontal U-shaped neck member 11 encircles the rear of the nape of the neck when the bonnet-like structure is in place on a head of hair. The ends of the front face member may be secured to the ends of the horizontal U-shaped member by sewing or by means of rivets 12, 12.

Above the U-shaped neck member and connected at spaced-apart points to the front face member, are horizontal U-shaped intermediate Marcel wave defining members 13, 13 which are preferably composed of flexible wire so as to exert pressure on a head of hair 70 when in place as a bonnet-like structure thereon as shown in Fig. 1. The members 13 may be of soft iron or soft steel, copper or brass or alloy, to reduce the cost thereof, and in order to prevent corrosion these metal 75 wires may be treated, covered with fabric or a coating of rubber or other water-proofing material or corrosion resisting material, as shown at 14 in Fig. 5, or the wires may be left bare if they have been treated to prevent 80 corrosion.

The forward ends of the intermediate U-shaped members 13 are permanently connected to the front face member at spaced-apart points along the same as shown in Fig. 95 1. For this purpose the ends of the wires 13 may be provided with eyes 15 which are inserted between the layers 16 and 17 so as to be imbedded in the face member 10 in position for riveting thereto. The rivets are

preferably provided with button-like heads 18 and prongs 19 and 20 which are pointed at 21 and 22 as shown in Fig. 6 to facilitate penetration of the layers 16 and 17 of the fabric on opposite sides of the wires 13 and back of the eyes 15. It will thus be seen that when the wires 13 are riveted to the face member 10 the upper and lower layers 16 and 17 will be clamped to the opposite sides 5 of the wires and as a further means of preventing dislodgment of the wires from the face member, the eyes 15 act as abutments against the prongs of the rivets. It will thus be seen that the ends of the U-shaped intermediate Marcel wave defining members are permanently riveted to the front face member and prevented from being withdrawn from such face member by reason of such rivets being engaged by the eyes 15. 10 A binding member 23 of flexible collapsible material such as silk braid or tape fabric extends from the rear central portion of the neck member to the rear central portion of the uppermost U-shaped member 13. The upper end of the binder is looped at 24 around the rear portion of the uppermost U-shaped wire member and a clip 25 relied on to permanently close the loop. The lower end of the binder 23 is connected at 26 to the rear central portion of the neck member 11 by being sewed thereto since the neck member is also of fabric. The intermediate U-shaped Marcel wave defining members being of flexible wire, I prefer to connect the binder 23 to the rear central portion of these U-shaped members by means of button rivets 27 having prongs 28 and 29 as shown in Fig. 6 to extend around the wire 13 on opposite sides thereof so that the binder may 25 serve to hold the rear portions of the U-shaped members 13 in spaced-apart relation when the bonnet-like structure is in place on a head of hair. Ribbons 30 and 31 may be riveted at 12, 12 to the lower ends of the face member 10 so that a bowknot 32 may be used under the chin for holding the bonnet-like structure in place. All of the members of the bonnet-like structure are permanently connected to 30 together and the U-shaped wire members will have sufficient resiliency and flexibility to fit a head of hair and press the same against the head along the dividing line between the Marcel waves desired. It will thus be seen that the single bonnet-like structure has the various members thereof permanently connected together so that when in use the front face member is adapted to fit across the upper portion of the forehead and extend down 35 in direct lines along the sides of the face of the person using the device. The neck member, the face member and the securing ribbons being all of fabric will be comfortable when engaging the skin of the wearer. Furthermore, the face member 10, the neck

member 11 and the binder 23 being of flexible collapsible material, the whole structure may be collapsed into a small flat space as illustrated in Fig. 2. When the bonnet-like structure is in operative position as shown in Fig. 1, a pencil 33 or other pointed instrument may be used to form the undulations of the hair between the Marcel wave defining members 13. 70

To Marcel the hair by the use of the structure shown in Fig. 1, the hair may be dampened or moistened, after which the marceling device is placed on the head and tied thereto by means of the bowknot 32. After this has been done the pointed instrument 33 may be inserted beneath the hair between the adjacent intermediate frame members 13. After this instrument has been sufficiently inserted it may be raised while in inserted position to project portions of the hair away from the head above the frame members 13. This may be repeated for raising the hair into waves between the various wires 13 which act as dividing lines between the waves. By having the wires 13 uniformly spaced from one side of the head around to the other side, uniform undulations may be produced. After these undulations have been formed by means of the pointed instrument 33, the bonnet-like structure is permitted to remain on the head until the hair is thoroughly dry, after which such structure may be removed to leave the undulations properly defined. 75 80 85 90 95

In the form shown in Fig. 7 the intermediate U-shaped Marcel defining members 13' are arranged for a pompadour head of hair, and for this purpose the wires are all approximately semi-circular and their ends riveted by means of button rivets 18 to the front face member 10. The lowermost U-shaped wires may be spaced closer together at their ends as shown at 34 in Fig. 7. To the lower ends of the face member 10 are secured at 12, 12 the collapsible neck member 11 and the tying ribbons 30 and 31. In the form shown in Fig. 1 the U-shaped members 13 are in the form of sections of ovals, but in Fig. 7 the U-shaped members 13' are approximately semi-circular. Therefore it is desirable in the form shown in Fig. 7 to provide two spaced-apart binding members as shown at 23', 23' in Figs. 7 and 8. The upper ends of the binders 23' are provided with loops 24 which are secured by means of the clips 25 in closed formation and the lower ends are sewed at 26, 26 to the neck member 11. The binders 23' are of braid or tape fabric and are riveted by means of button rivets 27 to the wire members 13' as shown in Figs. 7 and 8. 100 105 110 115 120 125

In the form shown in Fig. 1 and also in the form shown in Figs. 7 and 8, each of the U-shaped members 13 and 13' is composed of a separate length of wire, but in the form 130

shown in Fig. 9 a single wire 35 forms all of the U-shaped Marcel wave defining members. One end 36 is imbedded between the layers of fabric of the front face member 10 at the 5 upper central portion of the latter as shown in Fig. 9. The other end 37 is likewise imbedded between the layers of the front face member near one end of the latter. The ends of the U-shaped members may be looped as 10 illustrated at 38 so as to be adjacent the forward edge of the face member 10. Button rivets may be applied as illustrated at 39, 40, 41 and 42 so that the right angle portions or those portions parallel to the front edge 15 of the face member will act as abutments to prevent detachment of any U-shaped member from the front face member. The riveting by means of the button rivets 18 as illustrated at the right-hand portion of Fig. 9 20 is the same as that shown and described in connection with Figs. 1 and 5. The riveting of the binders 23' at 27 to the U-shaped wires shown in Figs. 7, 8 and 9 is the same as that illustrated in Figs. 2 and 6.

25 The resiliency of the wire members may vary with the material of which they are composed and when the bonnet-like structure fits the head of a person as desired the U-shaped Marcel wave defining members will have the 30 necessary pressure to hold the hair in place. However, it is preferred not to have the wire of spring metal but of sufficiently soft material that the user may bend the wires to secure a closer fit of the structure against the 35 hair on the head. When the wires are composed of relatively soft material such as soft iron, copper, brass or alloy so as to permit the wearer to bend the wires into proper shape without destroying their resiliency, 40 the ribbons 30, 31 may be used to assist such resiliency in holding the bonnet-like structure in place against the hair on the head. The use of soft iron lessens the cost of construction and by waterproofing the wires by 45 covering the same with rubber or other waterproofing material, corrosion of the wires will be prevented and, moreover, the structure can be kept in a very sanitary condition because the surfaces of the waterproofing material on the wires is smooth and can be easily cleaned.

50 Obviously those skilled in the art may make various changes in the details and arrangements of parts without departing from the 55 spirit and scope of the invention as defined by the claims hereto appended and I wish therefore not to be restricted to the precise construction herein disclosed.

Having thus fully disclosed an embodiment 60 of my invention, what I desire to secure by Letters Patent of the United States is:

1. A collapsible hair waving structure comprising an upright horseshoe-shaped front frame member of flexible collapsible material, 85 a horizontal horseshoe-shaped neck member

connected to said front upright member, intermediate relatively stiff horseshoe-shaped members connected at spaced-apart points to said front upright member, a binding member connected to all of the aforesaid intermediate members and to the neck member to aid in spacing said intermediate members apart when the structure is fitted to the head of a person, said binding member being of flexible collapsible material, and flexible tie members connected to said structure for fastening said structure in position on the head of a person.

2. A Marcel hair waver comprising a fabric U-shaped front member, spaced-apart horseshoe-shaped divisional members connected at their free ends to said front member, the rear ends of said divisional members being relatively concentric, a horizontal horseshoe-shaped fabric neck member having its free ends connected to the free ends of the front member, and a flexible rear member connected to the neck member and to the rear ends of said intermediate members.

3. A collapsible hair waving structure comprising a fabric front member, water-proofed relatively stiff metal members of U-shaped construction having their free ends attached to the fabric front member, a horizontal fabric neck member of U-shaped configuration having its free ends attached to said front member, a flexible rear member connecting the various stiff members and the neck member, and means for fastening the structure in place on the head of a person.

In testimony whereof I have signed my name to this specification on this 28th day of June, A. D. 1930.

JOHN J. RYAN.
